UNITED STATES PATENT OFFICE.

ALVIE C. CRIMMEL, OF HARTFORD CITY, INDIANA.

DESIGN FOR A LIQUID CONTAINER FOR FOUNTAIN SYRINGES.

Application filed February 17, 1922. Serial No. 754. Term of patent 3½ years.

To all whom it may concern:

Be it known that I, ALVIE C. CRIMMEL, a citizen of the United States, residing at Hartford City, in the county of Blackford and State of Indiana, have invented a new, original, and ornamental Design for Liquid Container for Fountain Syringes, of which the following is a specification, reference being had to the accompanying drawing, forming part thereof.

Figure 1 is an elevation of a liquid container for fountain syringes, showing my new design.

Figure 2 is a bottom plan view thereof.

I claim:

The ornamental design for a liquid container for a fountain syringe, as shown.

ALVIE C. CRIMMEL.
